C. BLAMFIELD.

FIRE LIGHTER.

APPLICATION FILED JAN. 29, 1918.

1,274,235.

Patented July 30, 1918.

Inventor,

Charles Blamfield;

By A. B. Upshur,
Attorney.

UNITED STATES PATENT OFFICE.

CHARLES BLAMFIELD, OF BOSTON, MASSACHUSETTS.

FIRE-LIGHTER.

1,274,235.

Specification of Letters Patent. Patented July 30, 1918.

Application filed January 29, 1918. Serial No. 214,387.

To all whom it may concern:

Be it known that I, CHARLES BLAMFIELD, a subject of Great Britain, and a resident of Boston, in the county of Suffolk and Commonwealth of Massachusetts, have invented 5 certain new and useful Improvements in Fire-Lighters, of which the following is a full, clear, and exact specification.

The object of this invention is to provide

10 an automatic fire lighter in compact and inexpensive form, which shall be capable of remaining in blaze until it has fully ignited the combustible material for which it is set, notwithstanding any wind or draft; which 15 shall be without a tendency to accumulate moisture during hours of waiting; which shall have sufficient blaze to overcome any dampness acquired by the kindlings; which may be adapted for igniting after any desired 20 interval of time; which may be used for igniting sticks of incense at appointed hours; for setting off fireworks automatically in the evening which were located in the daytime, and for other uses of equal 25 value.

In carrying my invention into effect I provide a small tube adapted to hold the head of a match in the path of a spring-impelled igniting plate, the latter being controlled 30 by a timing device, and the flame of the ignited match-head being made to strike a gauze impregnated with a special solution.

In the drawings, Figure 1 is a perspective view of the fire-lighter in its preferred form. 35 Fig. 2 is a longitudinal section of the same. Fig. 3 is a perspective view of the lighter adapted for igniting a stick of incense. Fig. 4 is a side view of the lighter arranged to be set off by means of an alarm clock. Fig. 40 5 is an under view of the device and Fig. 6 a cross section of a modification.

The main body of the lighter comprises an inexpensive tube 1 preferably composed of paper or the like, approximately rectangular in cross section and having an elongated opening 2 near its mid-length. Over this opening is secured, preferably by paraffin 8 in sufficient quantity to provide a strong and durable flame, a covering 3 of 45 gauze impregnated with a solution of rosin and wood alcohol. This solution renders the gauze both moisture proof and more sensitive to ignition.

For initiating combustion, a match head 50 or tip 4 is located near the gauze and a movable striking device provided. The latter

comprises a slidable carrier 5 having a curved metal striker 6 attached thereto, the latter being so curved as to give a slightly yielding cushion-portion 7 against which the 60 match-head is received; and a concaved igniting portion 9 designed to drag over the match-head. This igniting portion may be roughened mechanically, or provided with 65 friction paper.

To the side of the tube 1 opposite the opening 2 is attached a strip of wood 10 both for the purpose of stiffening the tube and for firmly holding the match in place. This strip may be glued to the tube, as the 70 majority of the figures of the drawing are designed to indicate, or it may be hinged thereto along an edge as shown in Fig. 6. In the former case, the strip is formed with a longitudinal slot 11, as indicated in Fig. 5, 75 having a locking lever 12 pivoted therein to leave a small open space at the pivotal end. This slot is wider than the head or tip of an ordinary match, and the pivoted end of the lever or lock 12 is provided with a finger 80 13 partially filling said open space. The lock 12 being swung outward, as shown in Fig. 3, space is left for the insertion of the head of a match until it reaches the igniter surface 7. Then the lock is pressed back in, 85 firmly wedging the match in place, and, if desired, the protruding portion can be broken off.

From the carrier 5 a waxed thread 14 passes out through a cork 15, terminating in 90 a loop. Preferably this loop is formed by doubling the thread over on itself and fastening both ends to the carrier. In this loop 17 exterior of the cork is placed a bit of soluble substance 19; and over the outer end 95 of the cork is put a cap 20 fitting the same liquid tight. A suitable liquid having been introduced within the cap prior to its application on the cork, the bit or lump 19 will slowly dissolve until the loop 17 is able to 100 cut through it and to permit the carrier to be drawn along the tube.

This movement of the carrier is caused by means of a helical spring 21 shown in Fig. 2, or by a rubber elastic 22 indicated in Fig. 4. In either case the result is the same. The instant the lump 19 becomes sufficiently soft, the elastic band or spring pulls the thread through the cork and draws the igniter 6 along the tip of the match-head 4. 110 The latter instantly ignites and sets the gauze 3 on fire, the flame therefrom rising

to a height of several inches and enduring for some minutes, entirely sufficient for igniting any ordinary kindlings placed above the kindler.

5 When the fire lighter is composed of paper and other combustible materials, it is usually consumed during its performance of its task; but it may be, if desired, constructed of metal, with the saturated gauze 10 and the soluble block 19 as the only parts to be renewed.

The small blocks or tablets 19, if composed of loaf sugar and the dissolving liquid water, will soften and release the igniter in a very 15 few minutes; and a tablet of potassium bromide will release in nearly half an hour. I prefer, however, to have the tablets composed of powdered rosin and soda, the proportions of which can be varied in accordance with the time-limits desired, the greater 20 the proportion of rosin the longer the tablet will remain hard enough to resist the solvent or disintegrating action of water. In weather of average temperatures, water 25 may be used in the caps 20, but where there is danger of freezing, denatured alcohol should be employed, and a modified tablet used.

To enable an alarm clock to be utilized for 30 actuating the fire lighter, the clock is located either near the edge of a shelf or other support, or suspended from any suitable hook, and an elongated weight 25 engaged at one end beneath the edge of the alarm bell 26, as 35 shown in Fig. 4, this weight connected by a cord 27 to a small hooked knife 29 engaged with the thread loop 17. When the alarm strikes, the vibrations of the bell will dislodge the weight; the latter in its fall causes 40 its string to jerk the knife 29, thereby cutting the loop, the carrier and igniter fly past the match-tip; the latter is ignited and the fire kindled.

When the strip 10 is hinged along an edge 45 to the tube 1 as shown in Fig. 6, a hole is made therein snugly fitting the match stem but too small for the tip 4. The match is therefore introduced into this hole from the inner surface of the strip when swung away. 50 The strip is then swung back and secured in place by a length of adhesive tape 30 wound around the parts. I prefer to use this tape with both forms of the device in order to provide a convenient means for suspending 55 the lighter from any suitable surface.

When the lighter is to be employed for igniting sticks of so-called incense, the cap 20 is provided with a socket 31 into which 60 an end of the stick can be inserted and so held with its other end at a point which will be met by the igniter flame. An end of a comparatively short fuse can be similarly supported for ignition at a predetermined time.

65 It is to be understood that the cap fits

liquid-tight the protruding portion of the plug or cork 15, and the fluid is not put therein until the igniter is set. It is well to provide a small vent 36 through the upper side of the cap 20 in order to prevent its 70 liquid from being forced by expansion into the interior of the tube through the small hole in which is the thread 17, and possibly reaching and damping the match tip.

I have found that when the thread 17 is 75 attached directly to the carrier 5, it is liable when released to carry with it a small amount of moisture which sometimes flies upon the match tip and extinguishes its flame. To prevent this is the object of the 80 two separable threads 14 and 17.

In order to keep the thread 17 from cutting into the cork or plug 15, and thereby running less freely through the latter, the thread is passed through a small bead 32, 85 as shown in Figs. 1 and 4.

It is best not to keep the spring or elastic 90 21, 22 in tension until just when put in use. For stretching the elastic device, a string or thread 33 having a tab 34 at its outer end is attached to the spring or elastic, in order to permit the latter to be drawn outwardly to the desired degree of tension, a hook 35 being provided at the mouth of the tube for the attachment of the tensioned member. 95 This hook performs the added function of a means of anchorage for the igniter under certain conditions.

I usually wind the cord or thread 27 about the igniter, and tuck its knife 29 beneath the 100 winds of the same, as indicated in Fig. 5, so that the device will be ready for use either with a liquid, an alarm clock or other retarding means, according as the weather conditions may be found.

105 What I claim is:

1. An igniting device comprising means for supporting a match or the like, a movable friction device, means for forcibly moving the latter, means including a soluble tablet holding the friction device from movement, and means for holding a liquid in contact with the tablet.

2. An igniting device comprising a tubular body having a lateral opening, a friction 115 device slidable within the body, elastic means acting on said friction device in one direction, means for supporting a match or the like in the path of the friction device, means temporarily holding the friction device inactive, and a fabric saturated with a combustible solution disposed on said lateral opening.

3. An igniting device comprising a tubular body having a lateral opening, a friction 125 device slidable within said body, elastic means acting on said friction device in one direction, a soluble tablet adapted to hold the friction device stationary, means for holding a liquid in contact with said tablet,

- means for holding a match or the like in the path of the friction device, a fabric disposed on said lateral opening, and combustible material attached to the tube about said fabric.
- 5 4. An igniting device comprising a tubular body having a lateral opening, a carrier 45
slidable therein, a curved friction device attached to said carrier, elastic means acting on said carrier in one direction, means for supporting a match or the like in the path 50
of said friction device beneath said opening, a plug in the end of said body opposed to said elastic means, a thread passing through said plug and looped exterior to said plug,
- 10 15 a tablet within said loop, and means for releasing said thread from the tablet at a predetermined time, the thread being connected with and anchoring said friction device.
- 15 20 5. An igniting device comprising a tubular body having a lateral opening, a carrier 55
slidable within said body, a friction device attached to the carrier, elastic means acting upon said carrier in one direction, means for supporting a match or the like in the path of 60
the friction device, a plug in the end of said tubular body opposed to said elastic means, a thread having its ends attached to said plug and its looped portion passing through
- 25 30 the plug to the exterior, a soluble tablet in 65
said loop, and a cap adapted to contain a liquid, fitting the outer end of the said plug, the liquid acting to dissolve said tablet.
- 20 25 6. An igniting device comprising a tubular body having a lateral opening, and a slot 70
in the side opposite the opening of a width to receive the head of a match, a locking lever pivoted at one end in said slot for locking a match therein, a friction device 75
slidable within said body for igniting the match, means for moving the friction device and means for temporarily holding the friction device inactive.
- 25 30 7. An ignition device comprising a tubular body having a lateral opening, a carrier 45
slidable within said body, a sheet metal friction device attached at one end to said carrier and having its other end curved away from the carrier and provided with a rough surface, means for holding a match or the like in the path of said roughened surface, means for moving said carrier and means for temporarily holding the carrier inactive.
- 30 35 8. An igniter comprising a tubular body having a lateral opening covered with a 55
fabric secured thereto, combustible material surrounding said opening, means for holding a match or the like beneath said opening, means for igniting the match and means for temporarily holding the igniting means 60
inactive.
- 35 40 9. An igniting device comprising a tubular body, a slideable friction device therein, means for holding a match or the like in the path of said device, elastic means acting on 65
said friction device in one direction, means for releasably holding the friction device, and a hook pivotally connected with the tubular body for anchoring the elastic means.
- 40 45 10. An igniting device comprising a tubular body, a slideable friction device therein, elastic means acting on the friction device in one direction, means for holding a match or the like in the path of said friction device, a plug at the end of the tubular body 70
opposed to said elastic means, a looped thread attached at its ends to the plug and passing through the latter, a soluble tablet in said loop exterior to the said body, a bead on said thread between the tablet and plug, and 75
a cap for liquid fitted to said plug and having a small vent through its upper wall.

In testimony that I claim the foregoing invention, I have hereunto set by my hand this 25th day of January, 1918.

CHARLES BLAMFIELD.
